BOOTJACK

David Oblusteele, Buffalo, N. Y.

Application September 27, 1948, Serial No. 51,326

1 Claim. (Cl. 223—115)

1

This invention relates to a combined bootjack and hanger, and more particularly to a type thereof which is adapted to be suspended from a suitable support when employed as a hanger, or to be collapsed for storage when not in use.

The object of the invention is to provide a structure of this character which will help the user to maintain his boots in excellent condition.

Another object of the invention is to provide a structure of the kind specified which can be converted from one use to the other by a simple manipulation of the parts thereof.

A further object of the invention is to provide a device, as and for the purposes set forth, which is extremely simple in construction and inexpensive to manufacture.

Other objects and advantages will be apparent during the course of the following description.

In the accompanying drawings forming a part of this application, and in which like numerals are employed to designate like parts throughout the same:

Figure 1 is a side elevational view illustrating the bootjack supporting a pair of boots;

Figure 2 is a front elevational view of the boot-jack with the parts in the position of Figure 1;

Figure 3 is a top plan view of the bootjack with the parts in the position of Figure 1;

Figure 4 is a side elevational view, illustrating the use of the bootjack for removing a boot;

Figure 5 is an enlarged sectional view taken on the line 5—5 of Figure 2.

Referring in detail to the drawings, the device comprises a flat elongated platform or foot rest 10 preferably fabricated of wood. A screw eye 11 secured to the platform 10 adjacent the top end thereof carries a ring 12 by means of which it may be suspended from a suitable support for use as a hanger for a pair of boots and other articles of personal use; the top end also being provided with a central aperture 14 for its like suspension and a pair of oppositely disposed notches 15 and 16 in the side edges thereof from which the aforesaid articles of personal use, such as clothing, fishing gear, and the like can be hung.

A triple hinge 17 is secured to the other end of the platform 10 and a portion of the hinge is secured by screws 20 to each of a pair of holders 18 and 19. The holders 18 and 19 are of similar construction and each is provided with a cut-out or recess 21 in its outer end and shaped to conform to that of the heel portion of a boot. For maintaining the holders 18 and 19 immobile with respect to the platform 10, a pair of oppositely

2

disposed braces 22 fabricated of a suitable metal are each detachably connected at one of their ends by means of screw eye 23 to the side edges of the holders 18 and 19 and have the other end of each provided with a slot 24 to jointly engage over the shank of a headed screw 26 which is secured in a side edge of the platform 10. A cord 27, Figure 1, is provided for each of the holders 18 and 19 and is trained through the screw eye 23 on the holders for releasably securing a boot 28 which is being supported thereon. Each of the holders 18 and 19 is provided with a metal strap 29, Figure 3, for a purpose to be subsequently described. The straps 29 have one end pivotally connected to the holders by a pin 30, and the other end of the strap 29 is provided with a slot 31 to engage under the headed end of a rivet 32 which projects from the holder. For causing pivotal movement of the straps 29, a curved finger-engaging portion 33 is formed on the end of the straps 29 adjacent to slot 31.

In use, referring to Figure 1, the bootjack is shown with the holders 18 and 19 arranged at right angles with respect to the platform 10 and releasably maintained in that position by means of the braces 22. Thus, Figure 1 illustrates a boot 28 (left side) having its heel supported on the holder 18 and its sole resting on the brace 29 which extends across the cut-out 21. The boot 28 is conveniently supported in this position, as when a wet boot is being dried, and the boot 28 is releasably secured thereon by means of the cord 27. The boot 28 (right side of Figure 1) is supported upside down on the holder 19, as for storage purposes and the boot upper rests on the brace 29 with the cord 27 trained over the boot for maintaining the latter immobile.

Referring to Figure 4, the bootjack is shown with its parts adjusted for use in removing a boot 28. Thus, the holder 19 is arranged so that it is in alignment with the platform 10, and the holder 18 is arranged so that it is at right angles to the platform 10 and provides a support for the latter. To remove the boot from the foot, the user places one foot on the platform 10 and places the back portion of the other boot in the recess 21 in the holder 19 and raises the foot out of the boot.

As many embodiments may be made of this inventive concept, and as many modifications may be made in the embodiment hereinbefore shown and described, it is to be understood that all matter herein is to be interpreted merely as illustrative and not in a limiting sense.

I claim:

In a boot jack, an elongated rectangular member constituting a platform, a triple leaf hinge having its central leaf secured to an end of said platform, a pair of boot supporting members of elongated rectangular form, each of the other leaves of said hinge being secured to a supporting surface of a boot supporting member adjacent to one end of the member, said supporting members being disposed in right angular relation with respect to each other and one of the same in alignment with the hinge supporting end of the platform, oppositely and inwardly inclined brace elements extending from the opposite side edges of said supporting members and of the platform, means detachably securing one of the ends of said brace elements to the said one supporting member and to said platform, and other means for securing the other ends of said brace elements commonly to the other of said supporting members, said platform and the said one supporting member being supported in inclined position by the other supporting member with the said one

supporting member extending from the upper end of the platform, said supporting members each having a recess in its outer end for the engagement of the heel portion of a boot therewith.

DAVID OBLUSTEEL.
